Primary Examiner — Katie Jane Stofko(74) *Attorney, Agent, or Firm* — Merchant & Gould P.C.(57) **CLAIM**

The ornamental design for a pet treat, as shown and described.

DESCRIPTION

FIG. 1 is a front, top, and left side perspective view of a pet treat according to the new design;

FIG. 2 is a left side elevational view thereof;

FIG. 3 is a right side elevational view thereof;

FIG. 4 is a front elevational view thereof;

FIG. 5 is a rear elevation view thereof;

FIG. 6 is a top plan view thereof; and,

FIG. 7 is a bottom plan view thereof.

The contrast in shading in FIGS. 1-7 represents a contrast in appearance only and does not represent any particular color, material, texture or finish.

1 Claim, 4 Drawing Sheets(56)
